SWITCH LOCK FOR RAILWAYS

Albert Edward Shirley, Toronto, Ontario, Canada

Application May 20, 1936, Serial No. 80,751

1 Claim. (Cl. 246—400)

My invention relates to improvements in switch locks for railways, and the object of the invention is to devise a lock for the switch lever which will insure of the switch lever being left in the down or inoperative position so that it cannot be swung upward to the operative position by providing means for preventing the withdrawal of the operating key in any other lever position than the down or locked position, and it consists essentially of the arrangement and construction of parts all as hereinafter more particularly explained.

Fig. 1 is a perspective view of a switch stand showing the operating lever thereof and the means for locking the same in the down position.

Fig. 2 is a vertical sectional view through the upper portion of the switch stand taken longitudinally through the mast arm and to one side of the operating lever and showing such lever in full in the down position and in dotted lines in the up position.

Fig. 3 is a perspective view of my lock removed from the mast arm.

Fig. 4 is a perspective detail of the locking mechanism removed from its casing and showing it in the locking position.

Fig. 5 is a similar view to Fig. 4 showing the mechanism in the unlocking position and the outer casing thereof in dotted lines.

Fig. 6 is an enlarged sectional plan view showing the means for securing the switch lock in the mast arm.

In the drawing like letters of reference indicate corresponding parts in the different views.

1 indicates a switch stand of any suitable construction provided with an upper quadrant plate or table 2 having end shoulders 2^x and 2° against which the switch lever 3 bears to hold the switch in the desired set position according to the usual practice.

4 indicates the lower portion of the target mast which is carried in the switch stand and to which is secured a mast arm 5. The upper portion of the mast arm 5 is extended at the outer end of the arm to form a receiving socket 6 into which the locking mechanism hereinafter described is held. 6^x is a slotted opening formed in the mast arm and extending inwardly from the centre of the recess 6. 7 is the outer casing of my lock 50 which fits the recess 6.

Within the casing 7 is fitted a block 8 having a central circular recess 8^x in its upper portion and a transverse rectangular recess 9 in its lower portion, such recesses merging one into the other 55 as indicated to form an intervening opening 9^x.

The recess 9 is preferably inclined as indicated. 10 is a bolt slidably fitting within the recess 9. 8° is a slot formed in the block 8 and extending therethrough and upward to the transverse recess 9 as clearly indicated in Fig. 5, such slot 5 opening extending at the back of the recess upward to the top of such recess. 11 and 12 are channels formed in the block 8 by which the recess 9 is drained of any moisture. The bolt 10 is provided with a transverse notch 10^x which is 10 the same width as the width of the slot 8°. 10° is a rack which is formed in the upper face of the bolt 10.

13 is a part gear held to rotate in the circular recess 8^x with its teeth extending through the 15 opening 9^x to engage the tooth rack 10° of the bolt 10. 13^x is a key orifice which is formed in the gear 13, the upper circular portion of the key orifice being concentric with the gear and through which extends a centre pin 14 from the 20 base of the recess with which the key for operating the lock is engaged in the usual manner when inserted in the key orifice 13^x.

The casing 7 forming the face plate of the lock is provided with a slotted opening 7^x registering 25 with the slotted opening 8° of the block. The slotted opening 7^x extends upwardly so as to be in horizontal alignment with the upper edge of the transverse notch 10^x of the bolt 10. The casing 7 forming the face plate is also provided 30 with a key orifice 7° corresponding in form to the key orifice 13^x. When the bolt 10 is in the locking position the key orifices 7° and 13^x are in alignment so as to permit of the insertion or withdrawal of the key.

The switch lever 3 is provided with a quadrant plate 3^x secured to or formed integral therewith, such quadrant plate forming an end shoulder 3° which, when the lever is in the downward position, is in alignment with the front face of the 40 bolt 10. When it is desired to operate the switch the key is inserted through the key orifices 7° and 13^x so as to turn the gear member 13 and thereby move the bolt 10 longitudinally against the pressure of the spring 15 thereby carrying the 45 notch 10^x into registering position with the vertical slots 7^x and 8°.

When in this position the switch lever 3 may be raised, the quadrant plate 3^x passing through the slots 7^x and 8° and through the notch 10^x 50 permitting the lever to assume the raised position shown by dotted lines in Fig. 2.

By the turning of the gear 13 as above described, the slotted portion of the key orifice 13^x is turned out of alignment with the slotted portion of the 55

key orifice 7^0 as clearly indicated in Fig. 5 so that the key cannot be withdrawn. The switch lever 3 is then swung horizontally to the desired position to operate the switch.

5 In order to hold the switch in the set position, the lever 3 must be swung down to the full line position of Fig. 2. By reason of the quadrant plate 3^x fitting within the notch 10^x of the bolt, the bolt 10 cannot be moved to the locking position until the operating lever is swung downwardly to the full line position and the key cannot be withdrawn from the key slot by reason of their being out of registering position or the position shown in Fig. 5. A switchman will, therefore, know that if he hasn't his key the operating lever of the switch will not have been set in the downward position. When the switch has been set and the lever is swung to the down position the bolt, by reason of the spring 15 or by 20 gravity, will return to its normal or locking position in front of the shoulder 3^0 and by such movement the gear 13 will be turned so as to bring the slotted portion of the key orifice 13^x into alignment with the slotted portion 7^0 thereby 25 permitting the withdrawal of the key. In other words, the key cannot be withdrawn until the operating lever 3 has been returned to its down position.

The casing 7 and block 8 are secured within the 30 recess 6 by screws 16 .

What I claim as my invention is:—

The combination with a switch stand, mast, and mast arm having a longitudinal slot extending through the bottom and front walls thereof and a rectangular recess in the front wall 5 centrally of and at the upper end of the slot, and a switch lever pivoted between the side walls of the aforesaid slot, of a rectangular block held in the rectangular recess and having a vertical slot extending therethrough from the bottom of 10 the block and registering with the slot of the mast arm, a transverse bolt receiving recess, the lower portion of which the vertical slot intersects, and a circular recess merging into the upper portion of the transverse recess, a gear fitting rotatably in the circular recess and having a key orifice therein, a front plate for the rectangular recess having a key orifice therein normally in a line with the key orifice of the gear, a bolt provided with a gear rack and meshing with the 20 aforesaid gear and slidably fitting the transverse recess and normally extending across the upper portion of the vertical slot and against the front face of which the upper portion of the lever normally engages until the bolt is moved from its 25 locking position to clear the lever end and permit its passage through the vertical registering slots of the front plate and block.

ALBERT EDWARD SHIRLEY. 30
